UNITED STATES PATENT OFFICE

2,502,534

TOP

Alten H. Ragsdale, Hemet, Calif.

Application March 6, 1946, Serial No. 652,444

1 Claim. (Cl. 46—73)

1

This invention relates to "tops" and more particularly to spinning tops or toys.

It is an object of this invention to provide a top of the type which will bounce while it is spinning.

Another object of this invention is to provide an attractive and novel type of top to bounce while it is spinning and which may be very simply made and assembled at a low cost.

Still another object of this invention is to provide a bouncing and spinning top which is constructed of few parts and the parts are of such a character that the whole assembly is durable enough to withstand hard and abusive use without any appreciable deterioration of the parts.

A further object of this invention is to provide a top of this character wherein the body of the top comprises the resilient means for causing the top to bounce.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a side elevation of a top constructed according to an embodiment of my invention,

Figure 2 is a top plan view of the top,

Figure 3 is a vertical section taken on the line 3—3 of Figure 1, and

Figure 4 is a bottom plan of the knurl.

Referring to the drawings, the numeral 10 designates generally a top, or assembly constituting a top, which is constructed according to an embodiment of my invention. The top 10 comprises a resilient body 11, made of soft rubber or other suitable resilient material. The body 11 is preferably of a generally oval configuration in vertical section and is formed with a semi-circular annular groove 12 approximately midway between the ends of the body 11. A flat cylindrical or disc-shaped portion 14 is formed at the upper end of the body 11.

The lower section of the top 10 is formed by an inverted dome-shaped sheath or cover 15 made of metal or plastic or any other suitably stiff material. The sheath 15 is adapted to cover the lower half of the body 11 and is fastened to the body 11 by an inwardly extending annular flange or rib 16, formed near the upper edge of the sheath 15, engaging in the groove 12 of the body 11. The sheath 15 is hollow having relatively thin side walls, but having a substantially thicker lower end or tip portion 17. This tip portion 17 is

2

formed with a vertically drilled opening 18 through the apex of the sheath 15.

An elongated pin 19 is carried by the sheath 15 slidably engaging in the opening or guide 18 and extending downwardly beyond the end of the sheath 15 to form a knurl for the top 10. Fixed to the upper end of the pin 19 is an enlarged disc 20 which engages between the lower end of the resilient body 11 and the inside of the tip end of the sheath 15, so that the knurl 19 is restrained from sliding downwardly from the sheath 15 and is resiliently supported against sliding movement upwardly.

In the use and operation of this top 10 the spinning is caused by the usual cord wrapped about the lower end of the top, and when it strikes the ground the disc 20 bearing against the rubber body 11 will cause the top 10 to bounce several times before settling down.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claim.

Having thus described my invention, what I claim is:

30 A spinning top comprising a hollow upwardly opening thin walled sheath, an inwardly extending peripheral bead about said sheath spaced from the upper open edge thereof, downwardly convergent side walls on said sheath, terminating in an apex having an axial opening therethrough, an elongated pin slidable in said opening and extending from said sheath, a head on said pin larger than said opening within said sheath and above said opening, a resilient body in said sheath 35 and extending thereabove, said body formed with an annular recess thereabout for engagement with said bead, the lower end of said body engaging said head for resiliently urging said pin downwardly through said opening.

40 ALTON H. RAGSDALE.
